FIG. 1.

FIG. 2.

MILES OVERHOLT

BY

Hazard C. Miller
ATTORNEYS.

UNITED STATES PATENT OFFICE.

MILES OVERHOLT, OF LOS ANGELES, CALIFORNIA.

DOLL.

Application filed March 2, 1921. Serial No. 449,097.

To all whom it may concern:

Be it known that I, MILES OVERHOLT, a citizen of the United States, residing at Los Angeles, in the county of Los Angeles and State of California, have invented new and useful Improvements in Dolls, of which the following is a specification.

It is the object of this invention to provide a doll adapted to form either a single relatively large doll, or such a doll, and a plurality of smaller dolls.

The invention contemplates the provision of a structure including the trunk and head of a doll and detachable limb forming members which when detached will have the appearance of smaller dolls.

The invention will be readily understood from the following description of the accompanying drawings, in which—

20 Figure 1 is a front elevation of a device constructed in accordance with the invention, and showing the limb members secured to the doll trunk.

Fig. 2 is an enlarged elevation of a portion of the doll structure with the dress of the same removed.

The doll includes a trunk and head portion which may be formed of suitable fabric material suitably stuffed. This trunk and head portion is shown as comprising the torso 1 and the head 2.

The arms for the trunk of the doll are shown as members 3 which are preferably also formed of fabric suitably stuffed and arranged to form separate smaller doll structures including the heads 4.

The head members are suitably painted or otherwise decorated upon one side to represent the back of the hands for the larger doll structure, and on their opposite sides are formed as the faces for the smaller dolls.

The smaller doll structures are swingably and detachably connected to the torso of the larger doll as by hook and eye connections 5—6. The arm members as thus provided by the smaller dolls are so connected that when hanging from the larger doll structure, the size of head members 4 representing the back of hands will be turned outwardly. By this arrangement one of the arm members may be swung across the body of the larger doll, so that the face forming the side of head member 4 is exposed.

The leg members for the larger doll are shown as doll structures 7 including heads

8 and preferably formed of fabric suitably stuffed. Arms 9 are provided for the doll structures 7 and are suitably swingably connected to the bodies of said smaller doll structures. The ends of arms 9 are provided with eyes 10, and the lower portion of the torso of the larger doll structure is provided with co-operating hooks 11, so that the two of the dolls 7 may be suspended from their arms from the larger doll structure in position to form legs for the same.

A second pair of the smaller dolls are preferably suspended from the ones which are attached to the body of the larger doll structure, and for this purpose the lower ends of the first set of smaller dolls 7 are provided with hooks 11^a adapted to engage the eyes 10 upon the arms of the second set of smaller dolls 7 in order that this second set may be suspended in manner similar to that previously described. The connections between the first and second sets of smaller dolls 7 will thus form the knee joints for the legs of the larger doll structure.

The body of the larger doll structure may be provided with a suitable dress 13, and the smaller dolls 3 and 7 are provided with dresses 14 of the same material so that when the complete larger doll structure is assembled, as just described, a complete dress 85 will be formed for the doll.

The dress 13 is preferably provided with a flaring portion 15 at its lower end which, when the first set of depending dolls 7 is in position, will overlie the heads and arms 90 of the depending smaller dolls. In similar manner the lower ends of the dresses 14 for the first set of smaller dolls are provided with flaring portions 16 adapted to overlie the heads and arms of the second set of depending dolls 7 when the latter are in position.

One of the smaller dolls 3 forming the arms of the larger doll structure, when swung across the body of the larger doll, is 100 arranged to have the appearance of a child carried in the arms, and means are provided for holding the arm in such position which, in the present instance, as shown as including a hook 17 upon the body of the larger 105 doll, and a ribbon 18 forming a part of the dress for the smaller doll 3 and so arranged as to be engaged by the hook.

It will thus be seen that I have provided an extremely simple structure whereby a 110

child is provided with either a single doll structure, or with such a doll, and a plurality of smaller doll members.

Various changes may be made without departing from the spirit of the invention as claimed.

What is claimed is:

1. A doll comprising a trunk, and limbs having hook and eye connections with said trunk and formed as separate dolls.
2. A doll comprising a trunk member, separate limb members formed as miniature dolls, and cooperating means for connecting the respective members in readily detachable relation.
3. A doll comprising a trunk, detachable limb members formed of separate dolls, and means for detachably and swingably connecting the limbs to the trunk.
4. A doll comprising a trunk, detachable members, and means for connecting the members to the trunk, said members forming separate dolls when detached from the trunk.
5. A doll comprising a trunk, a member

formed as a miniature doll, means for swingably and detachably connecting the member to the trunk so that the member may be swung across the body and supported as a smaller doll, or may hang at one side as an arm, the end of said member appearing as a hand upon one side and as a head for the smaller doll upon its opposite side.

6. A doll comprising a trunk, smaller dolls having arms, and means for detachably and swingably connecting the arms of the smaller dolls to the trunk to depend as legs.

7. A doll comprising a trunk, smaller dolls having arms, means for detachably and swingably connecting the arms of the smaller dolls to the trunk to form legs for the trunk, and a dress upon the trunk and arranged to overlie the arms and heads of the smaller dolls when the latter are arranged as legs.

In testimony whereof I have signed my name to this specification.

MILES OVERHOLT.
